CHARLES A. NELSON AND CHARLES W. LANG, OF UTICA, NEW YORK, ASSIGNEES TO
SAVAGE ARMS COMPANY, OF UTICA, NEW YORK, A CORPORATION OF NEW YORK.

AUTOMATIC RIFLE.

1,100,766.

Specification of Letters Patent. Patented June 23, 1914.

Application filed December 18, 1912. Serial No. 737,443.

To all whom it may concern:

Be it known that we, CHARLES A. NELSON and CHARLES W. LANG, citizens of the United States, residing at Utica, in the county of Oneida and State of New York, have invented certain new and useful Improvements in Automatic Rifles, of which the following is a specification.

The object of this invention is to provide 10 a gun having many of the desirable features of the gun set forth in the Savage Patent No. 839,517 but possessing, in addition to improvements which increase the simplicity of construction, durability, stability, safety and 15 general efficiency of a gun of that kind, the quality of being semi-automatic, that is, adapted by the back-pressure of the charge on explosion, to withdraw and eject the empty shell, breech a fresh cartridge and 20 cock the firing mechanism.

In the accompanying drawings, wherein the invention is fully illustrated, Figure 1 is a side elevation of the improved gun; Figs. 2 and 3 are inside elevations of the 25 stock and barrel sections, respectively, of the receiver and of the parts of the mechanism respectively associated with them; Fig. 4 shows the receiver-including part of the gun partly in right side elevation and 30 partly in section; Fig. 5 shows said part of the gun partly in left side elevation and partly in section; Fig. 6 shows the forearm, including part of the gun partly in side elevation and partly in section; Fig. 7 is a plan 35 of portions of the receiver, action slide and the means for returning the action slide to its normal position; Fig. 8 is a plan of the rear part of the forearm; Fig. 9 is an inside elevation of the stock part of the receiver 40 and the mechanism associated therewith, the latter appearing in a different position from that illustrated in Figs. 2, 4 and 5; Fig. 10 is a sectional view on line $x-x$ of Fig. 9, looking forward. Fig. 11 shows the trigger 45 in side elevation and plan; Fig. 12 shows the sear in side and rear elevation; Fig. 13 shows the sear-trip in side and front elevation; Fig. 14 is a perspective view of the cartridge stop or abutment and breech-bolt; 50 Fig. 15 shows the magazine platform blocking the advance of the breech-bolt after effecting ejection of the shell of the last cartridge in the magazine; Fig. 16 shows the hammer, trigger, sear and sear-trip in the 55 position they occupy on re-cocking but be-

fore the finger pressure on the trigger has been relaxed; and, Fig. 17 is a detail of the ejector.

The receiver or frame, substantially similar to that in the patent to Savage above-mentioned, comprises a stock section a' and a barrel section a'' which lie face to face when assembled, being interlocked by the mortise and tenon connections b and c (Figs. 2, 3, 7 and 9) and held together by the single thumb-screw d entered through the section a'' into section a' . f is the stock and g the barrel. h is the magazine, of the box type, suitably held in the receiver by the latch i substantially the same as in the said 70 Savage patent.

The action-slide is a bar j guided in a straight slot k in the inner face of receiver-section a'' and projecting through the front wall thereof; its rear end has a lateral knob 75 l for manually retracting the action slide, said knob being carried by a pivoted notched part or latch m of the action slide which moves in a slot n (Fig. 1) in receiver-section a'' and may engage with its hook m' a 80 notch m'' at the rear end of said slot to hold back the action slide when depressed against a spring o , and the forward end of said action-slide carries the lateral collar p traversed by the pin q . Directly under the barrel is a tubular spring-case r penetrating and guiding said collar and having longitudinal slots s in which pin q plays, the rear end of said spring-case being received by the front 85 wall of receiver-section a'' and the forward 90 end supported by the stirrup t having a dove-tailed base u entered into a lateral similarly shaped slot v cut in the under side of the barrel. A spiral spring w , housed in the case and interposed between the pin q and a suitable abutment x at the rear end 95 of the case, presses the action slide forward. The forearm y , suitably hollowed out to fit the under side of the barrel and house the spring-case and stirrup t and afford the necessary clearance to the action-slide latch m , is secured in place in a way calculated to produce a simple, stout and readily assembled construction, thus: It has a rearward tenon z fitting a mortise 2 formed in the 105 front wall of the receiver, the vertical surfaces of said tenon and mortise being curved in plan (Figs. 7 and 8) so that when the forearm is held in position by the screws 3 and 4 the joint thus produced prevents lat- 110

eral displacement of the forearm; the screw 3 enters the forearm and receiver at said joint, while the screw 4 is passed through the forearm, stirrup *t* and case *r*, being tapped into the stirrup and having a reduced end 4' which enters the barrel and so locks the stirrup against lateral movement (Fig. 6). The action slide has at its rear end the spaced lateral lugs 5 and 6.

10 The breech-bolt 7 is generally like the breech-bolt described in the said Savage patent, being guided by the side walls of the receiver, having a cheek-piece or wall 8 on one side resting on the action-slide (which, 15 being thicker than slot *k* is deep, projects therefrom) and abutted above by the top wall of the receiver; it has a firing pin 9, an extractor 10 coactive with projections 10' to hold the cartridge and, on the side thereof 20 relatively opposite to said cheek-piece, a longitudinal slot 11, and is otherwise formed and operates the same as in the said Savage patent (excepting that it lacks the means for blocking it against recoil), the slot 11 25 being adapted to receive the acting end of the ejector 12 which springs inwardly to throw the extracted shell out of the ejection aperture 13 in the receiver when the receding breech-bolt, by its extractor, clears 30 the shell from the barrel. The breech-bolt has a downwardly depending tail 7' fitting between the lugs 5 and 6 on the action-slide.

The ejector 12 is a lever having its fulcrum formed by a hook 12' (Fig. 17) engaging in an annular channel 12'' formed in the inner side of the head of a screw 14; the lever and screw-head are received in a communicating slot 12''' and countersink 13' and a spring 15 in the slot presses the 40 free or acting end of the lever outwardly, tending to hold it to the limit of outward movement thereof which is afforded by the contact of the inner end 12'''' of the lever against the bottom of the countersink.

45 The top wall of the receiver has a recess or chamber 16 formed immediately back of the barrel-breech, the object of which is to afford ample blow-back relief for the escaping products of combustion and gases on firing, which would otherwise be unduly confined in the relatively limited space formed by the top and sides of the receiver chamber, the underlying magazine and its contents, the barrel-breech and front end of the 50 breech-bolt and so interfere more or less with the free action of the parts and sooner or later foul the piece. For checking the fresh cartridge rising from the magazine at a position in line with and guiding it into 55 the barrel breech we employ the stop 17 shown in Figs. 3, 4, 5, 14 and 15 which is a slender elastic metallic strip having parallel upstanding cheeks 18 secured in a slot 19 in the top wall of the receiver by a transverse pin 20 and a spoon-shaped free end 21, its

said spoon-shaped end traversing chamber 16 and being normally slightly below the level of the top of the bore so that on yielding to the upward pressure of the magazine spring it will occupy such a position relatively to the bore as then to perform its function properly as a guide to the cartridge in breeching the same. 70

In order to insure the breech-bolt (which is the only freely removable element of the mechanism) remaining properly assembled with the receiver section *a''* on taking down we provide the member 17 with a lug 22 which is received by the groove 22' at the top of the breech-bolt. 75

The hammer 23, having the head 24 to impinge against the firing-pin and the cam-face 25 to receive the wiping action of the lug 6 on the action slide, in cocking the hammer, and the spring-pressed thrust-bar 26 for the hammer are substantially the same. 80 as in said Savage patent.

The trigger 27, in the form of a rearwardly open housing, is fulcrumed at its mid-upper portion on the pin 28, being protected by the usual guard 29 affording a backing for the magazine. On the pin 28 is fulcrumed the sear 30 having the forwardly, rearwardly and long downwardly projecting arms 30', 30'' and 30'''. On a pin 31 in the trigger is fulcrumed the sear-trip 32 having the forwardly curved upper arm 32' and the downwardly projecting arm 32'' and on its upper arm the shoulder 32''' to engage under the end of arm 30'' of the sear. A spring 33 interposed between the lower arms of the sear and sear-trip tends to turn them in opposite directions on their fulcra. The hammer has a cocking notch 23' to be engaged by the arm 30' of the sear, and, back of said 95 notch, a cam-surface 23'' to be engaged by the arm 32' of the sear-trip, and, forward of said notch, the concentric surface 23'''. 100

A plate spring 34 pressing downwardly on the locking-bar 35, suitably guided in a slot in the thrust-bar 26 and stepped on a cross-pin 36 in the rearwardly projecting arm of the trigger, through the thrust-bar forces the trigger forward, normally holding the upper edge of its front wall 27' in contact with the sear arm 30', which rests against the hammer; the locking-bar (movable upwardly under the influence of the trigger and also forward and backward pivotally on the cross-pin 36) is received by a slot 37 in the receiver and is moved forward or backward to bring one of its stepped shoulders 35', 35'' under the shoulder 35''' at the rear of said slot by the usual slide 38 which is penetrated by a stud 39 on the locking-bar. 110 The action of these parts is as follows: The parts being in the cocked position (Fig. 4) rearward movement of the trigger causes the sear trip, whose fulcrum is in the trigger, to trip the sear (fulcrumed on the sta- 115

120

125

130

tionary pin 28) so that the hammer falls; spring 33 meanwhile holds both the sear and sear trip against the hammer and as the hammer falls its cam 23" wipes the sear trip out of engagement at its shoulder 32" with the sear arm 30", while the sear arm 30' wipes over the concentric surface 23'" of the hammer.

If (there being no charge in the gun) the 10 hammer remains down, as in Fig. 9, the trigger will at this time be held from any lost motion, being retained against the sear arm 30', which itself abuts the hammer, by the shoulder 35' of locking bar 35 engaging shoulder 35''''. If, recoil occurring from an exploded charge, the hammer is thrown back, the sear, being clear of the sear trip and hence of the trigger, is free to act independently of the trigger to engage the hammer notch 23' and cock the hammer although (as will usually be the case) the operator's finger has not allowed the full return of the trigger (Fig. 16) which, when it does move forward, brings the sear trip 25 opposite the low part of cam 23" whereby it will be allowed to again assume dogging relation to the sear.

In the cocked position of the parts the trigger may be locked by moving the slide 38 rearward so as to bring shoulder 35" on the locking bar under the shoulder 35''''. The stud 39 is sufficiently longer than the slide is thick so that with the trigger forward (hammer cocked) its extremity is approximately flush with the top of the slide; with the trigger back (hammer down) the stud projects, indicating to the operator's thumb the uncocked condition of the piece.

The magazine *h* has the usual platform 40 to elevate the cartridges contained therein and to lock the breeching movement of the breech-bolt upon the magazine becoming empty (Fig. 15), the same as in the patent to Savage No. 885868.

45 Operation: The operation will be apparent to those familiar with this class of guns. To breech the first cartridge in the magazine the action slide *j* is retracted and then allowed to return under pressure of spring 50 *w*, forcing the cartridge (which has been meanwhile pressed by the platform 40 into the grip of the devices 10 10' on the breech-bolt) into the breech. Upon the gun being now fired the recoil of the breech-bolt, 55 through the action-slide, throws back the hammer which is immediately cocked, while the spent shell is extracted and ejected and, on the return of the action-slide and breech-bolt to their normal positions, a fresh cartridge breeched. When the last cartridge 60 has been exploded the breech-bolt and action-slide will be locked back by the platform 40 rising and blocking the return of the breech-bolt as illustrated in Fig. 15, thus 65 indicating that the piece is empty. To now

re-charge the piece, the action-slide is locked back by the latch *m*, the empty magazine withdrawn and a loaded one substituted, whereupon, the latch being released, the breech-bolt will in advancing pick off the 70 uppermost cartridge and breech it in the usual way, ready for firing.

Having thus fully described our invention, what we claim as new and desire to secure by Letters Patent is:—

75 1. In combination, the receiver, the hammer movable therein and having a cocking notch, a sear engageable with said cocking notch, and means for tripping the sear including a sear-trip normally engaged with the sear but hammer-tripped out of engagement therewith and a common means to hold said sear-trip engaged with the sear and the sear against the hammer.

80 2. In combination, the receiver, the hammer movable therein and having a cocking notch and a cam, a sear engageable with said cocking notch and means for tripping the sear including a sear-trip normally engaged with the sear but cam-tripped out of 85 engagement therewith and a common means to hold said sear-trip engaged with the sear and the sear against the hammer.

90 3. In combination, the receiver, the hammer movable therein and having a cocking notch and a cam, a trigger movable in the receiver, a sear movable in the receiver and engageable with the cocking notch, a sear-trip movable in the trigger and normally engaged with the sear but adapted to be 95 tripped out of engagement therewith by the hammer cam, and a common means to hold 100 said sear-trip engaged with the sear and the sear against the hammer.

105 4. In combination, the receiver, the hammer movable therein and having a cocking notch, a hollow trigger movable in the receiver, and trigger-released means for maintaining the hammer cocked housed in the trigger and having a part thereof movable in the receiver.

110 5. In combination, the receiver, the hammer movable therein and having a cocking notch, a hollow trigger movable in the receiver, and trigger-released means for maintaining the hammer cocked housed in the trigger and having a part thereof movable in the trigger.

115 6. In combination, the receiver, the hammer movable therein and having a cocking notch, a hollow trigger movable in the receiver, a sear movable in the receiver and engageable with said cocking notch, and a hammer-controlled sear-trip movable relatively to and supported by the trigger and actuated thereby to trip the sear, said sear and sear-trip being housed in the trigger.

120 7. In combination, the receiver, the hammer movable therein and having a stepped surface forming a cocking notch, a sear en- 130

gaging, and movable in the receiver to clear, said notch, means, including a trigger movable relatively toward and from the hammer, for releasing the sear, said sear projecting between the hammer and trigger and abutting the hammer and abutted by the trigger, and yielding means opposing the releasing movement of the trigger.

8. In combination, the receiver, the hammer movable therein and having a cocking notch, a trigger, trigger-released means engageable with the cocking notch to hold the hammer cocked, and a stop against which the trigger bears when retracted, said means being interposable between the hammer and trigger in the released position of the former and when the latter abuts said stop and acting to lock the trigger against said stop.

9. In combination, the receiver, the hammer movable therein and having a stepped surface forming a cocking notch, a sear engaging, and movable in the receiver to clear, said notch, means, including a trigger movable relatively toward and from the hammer, for releasing the sear, said sear projecting between the hammer and trigger and abutting the former and abutted by the latter, and means to stop the trigger in the sear-releasing movement thereof substantially at a point in such movement where the same will abut the sear and the sear simul-

taneously abut the higher portion of said stepped surface of the hammer in the released position of the latter.

10. A gun having a cockable hammer, a sear to hold the hammer in cocked position and a trigger to actuate the sear, said trigger being movable on retraction against a fixed part of the gun and said sear being movable on release of the hammer into interposed relation to and mutual contact with the trigger and hammer and thereby holding the former retracted.

11. In combination, the barrel, the receiver, the firing mechanism including the hammer and trigger each pivoted in the receiver and also having means to lock back the trigger on retraction thereof and consequent release of the hammer, and the spring-pressed member 35 normally holding the trigger in its forward position and adapted to abut the receiver on rearward movement of the trigger to limit such movement.

In testimony whereof we affix our signatures in presence of two witnesses.
